UNITED STATES PATENT OFFICE

CLARENCE P. AGER AND ARCHIE L. FROST, OF TACOMA, WASHINGTON, AND ADOLPH P. DEMMER, OF MINNEAPOLIS, MINNESOTA

FOOT GUARD

Application filed November 13, 1929. Serial No. 403,864.

This invention relates to foot guards to be placed in railway switches and frogs, and has for its objects to provide a metal guard which is easily secured in place; which may be removed therefrom without interfering with the rails; which requires a shorter bolt; in which the bolt-head engages a metal surface; and which is effective in use and cheap to install and maintain.

10 We attain these and other objects by the devices and arrangements illustrated in the accompanying drawings, in which—

Fig. 1 is a plan view of a railway frog, showing three pairs of foot guards mounted 15 therein; Fig. 2 is a section thereof on the line 2—2 in Fig. 1, the section of one such foot guard being taken at the fastening bolt; Fig. 3 is a similar section showing the guard being placed in position; and Fig. 4 is a rear 20 view of the guard removed from the rail.

Similar numerals of reference refer to similar parts throughout the several views.

As is well known, a foot guard is provided for the purpose of preventing a person's foot 25 from being caught between two rails when their heads are close together, being separated by a distance of from about three to five inches, as required by the Interstate Commerce Commission. These guards have 30 usually been constructed of wood, and when so made, they do not last long and are difficult to replace because the rails are close together and the bolt passes entirely through them and extends laterally therefrom. Also they 35 are apt to loosen by the wear of the bolt heads in the wood and, therefore, require constant inspection to see that the bolts are kept tight.

As seen by the drawings, our guard 40 consists of a flat unbroken front plate 1, extending in a straight line from the lower corner of the rail head 2 to the upper corner of the rail base 3. A back plate 4 is fixedly secured to the inner side of said front plate 1, preferably by welding, said plate 4 being secured thereto at a point slightly below the upper edge of the main or front plate 1. This back plate 4 extends inward under the rail head 2, and is then bent downward at 45 to lie in contact with the web 6 of the rail. This back

plate 4 is provided, at suitable intervals, with rectangular slots 7 extending up from its lower edge to a point adjacent to its bend 5. These slots 7 are positioned in accordance with the standard spacing adopted by the railroad for the carriage bolts used in fastening the ordinary wooden foot guard in place. One of the advantages of our foot guard is that the carriage bolt used may be substantially shorter than that needed for the wooden foot guard. The carriage bolt 8 has, of course, a square neck which is adapted to fit in the slot 7 formed in the back plate 4 of the foot guard, thus preventing the bolt 8 from turning when the nut 9 is screwed on its end.

As shown in Fig. 3, it is clear that, when this foot guard is being placed in position, the carriage bolts 8 are first inserted through the holes 10 in the rail web 6 and the nuts 9 and washers 11 are screwed a short distance only thereon. Then the foot guard may be passed downward between the rail heads 2, in a substantially vertical position, until the back plate 4 thereof engages the heads of the bolts 8 in its slots 7. At this point, the bend 5 in the back plate 4 passes the lower corner of the rail head 2, and the foot guard may then be easily slipped into position, as shown in Fig. 2, after which the nuts 9 on the carriage bolts 8 may be tightened up, drawing the back plate 4 and the foot guard plate 1 tightly into position.

It is, of course, to be understood that the above-described foot guard may be varied within the terms of the appended claims, for instance, the back plate 4 may be made integral with the front plate 1. However, the above-described form of our invention is that which we have preferred.

Having, therefore, described our invention, what we claim is:

1. A railroad foot guard comprising a front plate having an unbroken surface and extending between the rail head and the rail base; a back plate extending inward therefrom to the rail web and bent downward to lie against the rail web; slots formed in said back plate, extending upward from its lower edge towards the bend therein; and square-necked bolts passing through the rail web

and lying in said slots, the heads of said bolts adapted to engage the front side of said back plate, whereby the foot guard may be slipped downward past the rail head into engagement with said bolts when the bolts are loosened and drawn and held in position when the bolts are tightened.

2. A railroad foot guard comprising a front plate having an unbroken surface and extending between the rail head and the rail base; a back plate fixedly secured thereto at a point below the upper edge thereof and extending inward therefrom to the rail web; slots formed in said back plate, extending upward from its lower edge towards the bend therein; and square-necked bolts passing through the rail web and lying in said slots, the heads of said bolts adapted to engage the front side of said back plate, whereby the foot guard may be slipped downward past the rail head into engagement with said bolts when the bolts are loosened and drawn and held in position when the bolts are tightened.
